UNITED STATES PATENT OFFICE.

LOUIS CAMILLE CALAME, OF BIENNE, SWITZERLAND.

DESIGN FOR A WATCHCASE.

SPECIFICATION forming part of Design No. 36,228, dated February 17, 1903.

Application filed June 12, 1902. Serial No. 111,413. Term of patent 14 years.

To all whom it may concern:

Be it known that I, LOUIS CAMILLE CALAME, a citizen of the Republic of Switzerland, and a resident of Bienne, Switzerland, have invented and produced a new, original, and ornamental Design for a Watchcase, of which the following is a specification.

The design is illustrated in the accompanying drawings, in which—

10 Figure 1 is a view of the back of the watchcase, and Fig. 2 is a front view of said case.

The leading feature of the design consists in the ornamentation, as shown in the drawings.

15 On the center of the back of the watch are three figures—one a woman, holding in one hand an olive-branch, in the other an equi-angle, is sheltering two workmen standing on

each side of her. At her right a blacksmith is representing work in the factories. At her ²⁰ left is a miner. In the background are seen on one side a factory and smiths' tools, on the other the entrance to a mine and a trolley loaded with coal. At the feet of the three figures there are a broken sword and chain. ²⁵

The design of the front consists simply of a circular line or rib.

What I claim is—

The ornamental design for a watchcase as herein shown and described. ³⁰

In witness whereof I have hereunto set my hand in presence of two witnesses.

LOUIS CAMILLE CALAME.
